J. L. FOLSOM.

CARPET.

No. 15,768.

Patented Feb. 3, 1885.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 15,768, dated February 3, 1885.

Application filed August 6, 1884. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 The design consists of three large flower groups arranged as shown in the accompanying photograph.

The group A is shown in the lower center of the photograph, and in part at the left center edge and at the upper edge. It consists of a large central mass of geranium leaves and small flowers. On the right, above, is a small blossom spray and a projecting fern, and a group of geometric work. On the right, below, is a large projecting cluster of mossy leaves and stems, shown mostly at the left edge of the photograph. Below are several open leaf and blossom sprays, having a small group of S-shaped geometric work. On the left are 25 two fern sprays, and above are an open blossom spray and a small group of Greek crosses.

The group B is shown at the left upper part of the photograph. It consists of two or three large leaves as a central mass. Below, to the

right, is a large fern spray, having a small 35 group of geometric work. Below, to the left, are several small fern sprays. On the left is some geometric work, and above that a long leaf spray. Above are two leaf sprays and a block of small squares. On the right are two 40 small sprays.

The group C is shown at the right upper part of the photograph. It consists of a central mass of large open leaves, a fern spray above to the left, and one below, a leafspray— 45 one on the left and one on the right above— two moss sprays below, and a small group of skeleton leaves on the right. Small blocks of geometric work fill in the spaces between the sprays, and form part of the group. 50

I claim—

1. The design for a carpet, consisting of the group A, substantially as shown and described.

2. The design for a carpet, consisting of the 55 group B, substantially as shown and described.

3. The design for a carpet, consisting of the group C, substantially as shown and described. 60

4. The design for a carpet, consisting of the groups A, B, and C, substantially as shown and described.

JAS. L. FOLSOM.
